US0D1093406S

(12) **United States Design Patent** (10) Patent No.: **US D1,093,406 S**
(45) Date of Patent: ** Sep. 16, 2025

(54) **DISPLAY SCREEN OR PORTION THEREOF WITH GRAPHICAL USER INTERFACE**

(71) Applicant: **Masimo Corporation**, Irvine, CA (US)

(72) Inventors: **Keith Ward Indorf**, Lake Elsinore, CA (US); **Prianjali Kapur**, Turin (IT); **Lara Garreffa**, Turin (IT); **Manuela Bertaglia**, Carignano (IT); **Emma Constant**, Craponne (FR); **Xavier Blanc Baudriller**, Turin (IT)

(73) Assignee: **Masimo Corporation**, Irvine, CA (US)

(**) Term: **15 Years**

(21) Appl. No.: **29/909,544**

(22) Filed: **Aug. 7, 2023**

(51) LOC (15) Cl. **14-04**
